UNITED STATES PATENT OFFICE.

CLEMENS DZIEGIELEWSKI, OF DETROIT, MICHIGAN.

VEHICLE-DOOR LATCH.

1,218,845.

Specification of Letters Patent. Patented Mar. 13, 1917.

Application filed June 12, 1916. Serial No. 103,205.

To all whom it may concern:

Be it known that I, CLEMENS DZIEGIELEWSKI, a subject of the Czar of Russia, residing at Detroit, in the county of Wayne and State of Michigan, have invented certain new and useful Improvements in Vehicle-Door Latches; and I do declare the following to be a full, clear, and exact description of the invention, such as will enable others skilled 10 in the art to which it appertains to make and use the same.

This invention relates generally to latches, and more particularly to certain new and useful improvements in vehicle door latches. 15 The primary object of the invention is to provide a latch for vehicle doors having means for actuating the same from the outside of the vehicle, and an additional means for actuating the latch from the inside of 20 the vehicle, said additional means being wholly independent of the first mentioned means.

Another object of the invention is to provide a device of this character which will be 25 of simple, strong, durable and inexpensive construction, efficient and reliable in operation, and well adapted to the purpose for which it is designed.

With these and other objects in view, the 30 invention consists of certain novel features of construction, and the combination and arrangement of parts as will be hereinafter fully described and claimed.

In the accompanying drawing in which 35 similar reference characters designate like parts throughout the several views:

Figure 1 is a side elevation of a portion 40 of a vehicle door, showing a device constructed in accordance with this invention applied thereto;

Fig. 2 is an end view of the same;

Fig. 3 is a vertical sectional view through 45 the casing of the latch, illustrating more particularly the mechanism for operating the latter;

Figs. 4 and 5 are horizontal sectional views taken on the lines 4-4 and 5-5 of Fig. 3, respectively;

Fig. 6 is a vertical sectional view taken on 50 the line 6-6 of Fig. 3; and

Fig. 7 is a horizontal sectional view taken on the line 7-7 of Fig. 3.

Referring more particularly to the drawings, the reference character A designates a 55 vehicle door to which the present invention is more particularly designed to be applied,

the inner side of this door being provided with a recess of suitable configuration to receive the casing 1 of the latch. This casing 1 comprises a face plate 2 having a laterally extending end plate 3 extending from the outer edge thereof, and is provided at its upper edge with an upwardly extending portion 4, the latter having lateral flanges 5 arranged on its upright sides to provide 60 in effect guides for a purpose to be herein-after described. The upper end of the upwardly extending portion 4 and the face plate 2 are provided with vertically aligned openings 6 through which the knobs 7 of the 65 operating spindles extend to be connected to the latter. The end plate 3 is provided with a rectangular opening 8 through which the latch or bolt is projected. The reference numeral 9 designates the inner plate of the 70 casing 1, said inner plate being secured to the face plate in any convenient manner and being provided with an upwardly extending portion 10 disposed opposite the upwardly 75 extending portion 4 of the face plate, thereby properly housing the latch mechanism in the casing. 80

Slidably mounted within the casing 1 is a horizontal bolt 11, the outer end of which is beveled in the usual manner, while its inner end engages one end of a spiral spring 12 secured in any suitable manner within the casing. One side of the bolt 11 is provided with an arcuate recess 13 which coacts with a cam member 14 on a horizontal spindle 15, whereby to actuate the bolt, it being understood that the latter is provided with a longitudinally extending slot 16 to allow said spindle to project through the same. It may be seen from this construction that under the tension of the spring 12, the bolt 90 is normally held in its protracted position, but may be retracted upon actuation of the spindle 15. 95

The bolt 11 is provided with an inclined portion on its upper edge, here shown as being in the form of an upwardly extending lug 18 having one of its edges inclined. Slidably mounted between the flanges 5 within the upwardly extending portion 4 of the casing, is a vertical reciprocating member or bar 17. The lower end of this bar 17 is cut off angularly and bifurcated to receive an anti-friction roller 19. Arranged longitudinally of the bar 17 is an undercut slot 20 105 in which is received a coiled spring 21, one end of the latter resting against one end of 110

the slot 20, while its other end rests against a stop 22 carried by the casing. This spring 21 normally holds the bar 17 in its uppermost or retracted position. The upper end 5 of the bar is bifurcated as at 23 for engagement with the cams 24 carried by a second horizontal rotating spindle 25. By this arrangement, upon actuation of the spindle 25, the bar 17 is moved downwardly, the 10 lower end thereof engaging the inclined lug 18, it being understood that the latter is arranged in the path of the same, whereby the bolt 11 is moved into its innermost or retracted position. It may also be understood 15 that the bolt 11 is operated by the spindle 25 wholly independent of the spindle 15.

The device will be found very convenient for use in connection with the swinging doors of automobiles, for it provides a means 20 for operating the latch from either side of the door, the upper spindle 25 being connected to the knob 7 which extends beyond the inside of the door, while the lower spindle 15 is connected to a second knob which 25 is arranged on the outside of the door and in a plane considerably below the plane of the inner knob, the advantages of which will be obvious.

From the foregoing description, taken in 30 connection with the accompanying drawing, the construction and operation of the device will be readily understood without a more extended explanation.

As various changes in the form, proportion 35 and the minor details of construction may be resorted to without departing from the spirit of this invention, I do not wish to be limited to the construction herein shown and described other than that set forth in 40 the appended claims.

I claim:

1. A device of the class described comprising a casing, a horizontal bolt slidably mounted in said casing and having means 45 for actuating the same, a vertical guide in said casing, a vertical bar reciprocating in said guide and having a longitudinally extending undercut slot therein, coacting means arranged on said bar and said bolt 50 for operating the latter independent of the first named means, means for reciprocating said bar, a stop arranged in said casing, and

a coiled spring disposed in said undercut slot and having one of its ends engaging one end of the same, the other end of said spring 55 engaging said stop for normally holding said bar in its retracted position.

2. A device of the class described including a casing having a rectangular plate, a laterally inwardly extending flange formed 60 on one end of said plate and having a bolt receiving opening therein, an elongated portion extending upwardly from the upper edge of said plate and being slit transversely from each edge, the portion between said 65 plate and said slits being bent laterally inward to form parallel flanges and to leave an enlarged upper end, a laterally and inwardly extending tongue struck from said elongated portion at a point adjacent said 70 plate, a second plate abutting said flanges and having an enlarged upper end, said end having lateral flanges on its edges abutting the inner face of the first named enlarged portion, means for securing said plates together to form a guideway, a second rectangular plate having upper and lower lateral flanges abutting the inner face of the first named rectangular plate and secured thereto, a horizontally slideable bolt mounted 75 between the two rectangular plates and sliding through the opening in the first named flange, a lug on the upper edge of said bolt having an inclined face, a vertically movable slotted bar in said guideway, a coiled spring 80 in said slot, said tongue extending through said slot and contacting the lower end of said coiled spring and acting as a stop therefor, the upper end of said spring contacting the upper end of said slot, the lower end of 85 said bar coacting with the upper inclined face of said lug, an operating cam engaging the upper end of said bar and a second operating cam engaging said bolt whereby said 90 bolt may be operated by one cam independently of the other.

In testimony whereof I have hereunto set my hand in presence of two subscribing witnesses.

CLEMENS DZIEGIELEWSKI.
